(No Model.)

M. B. McCASTLINE.
CARPET FASTENER.

No. 362,171.

Patented May 3, 1887.

John G. Raymond
Smith

Inventor —

Minnie B. McCastline

UNITED STATES PATENT OFFICE.

MINNIE B. McCASTLINE, OF SYRACUSE, NEW YORK.

CARPET-FASTENER.

SPECIFICATION forming part of Letters Patent No. 362,171, dated May 3, 1887.

Application filed March 16, 1887. Serial No. 231,076. (No model.)

To all whom it may concern:

Be it known that I, MINNIE B. McCASTLINE, of Syracuse, county of Onondaga, in the State of New York, a citizen of the United States, 5 have invented certain new and useful Improvements in Carpet-Fasteners, of which the following is a specification, reference being had to the accompanying drawings, in which—

Figure 1 is a sectional elevation on the line 10 of the tack. Fig. 2 is a like view on the line of the retaining-rod; Fig. 3, a like view of the base and fastening; Fig. 4, a view like Fig. 1, showing different base; Fig. 5, a view like Fig. 2, showing base of Fig. 4; Fig. 6, a view like 15 Fig. 1, showing another base; Fig. 7, a like view of Fig. 6 on the line of the retaining-rod; Fig. 8, a view of the base and its fastening shown in Fig. 7; Fig. 9, a sectional elevation showing another base; Fig. 10, a sectional elevation showing another base; Fig. 11, a sectional elevation showing another base and follower.

My invention relates to that class of carpet-fasteners in which the carpet is secured by permanent tacks projecting above a base which is secured to the floor adjacent to the base-board; and it consists in the several novel features of construction and operation hereinafter described, and specifically set forth in the claims 30 hereunto annexed.

It is constructed as follows:

A represents the base in all of the figures of the drawings, consisting of a strip of wood or metal of one of the several forms shown, and 35 which is secured to the floor by a nail or screw, 1, so that at least one face will lie against the base-board. In this base I secure the tacks or spurs 2, the points of which project outwardly from the base. At the proper points I also 40 secure in the base the threaded rods 3, each of which is provided with a set or thumb screw of any desired form.

B is my follower, consisting of a strip of wood or metal of one of the forms shown, perforated to receive the outer ends of the tacks, 45 as shown, at any angle desired, and also to receive the rods 3 at any desired angle. These

rods 3 are slotted or cross-bored to receive a key, 4.

C is an ornamental cap-molding, of wood or 50 metal, (metal is shown in the drawings,) perforated at intervals in its length to permit the rods 3 to pass through it. This cap consists of a front face, 5, a downward flange, 6, upon its back side, and an inward flange, 7, upon its 55 front side. The flange 6 rests against the base-board, and the flange 7 rests upon the carpet.

In the several figures the dotted line 8 represents the carpet.

It operates as follows: Having provided the base with the tacks 2 and rods 3, I secure it to the floor. I then draw up the edge of the carpet and press it down upon the tacks. I then put on the follower over the rods 3 and press 55 it down thereon until the points of the tacks enter or pass through it, and when down tight I insert the keys 5 through the rods 3, thus holding the follower in place. I then put on the cap C and screw down the thumb-screws. 70

It will be observed that I can use a perforated washer upon the rods 3 in place of the follower, or a follower in such case composed of short pieces.

What I claim as my invention, and desire 75 to secure by Letters Patent, is—

1. A carpet-fastener consisting of a base provided with projecting tacks, a follower fitting upon said tacks, a cap-piece, and retaining-rods passing through the base, the follower, 80 and the cap, substantially as shown and described.

2. A carpet-fastener consisting of a base provided with projecting tacks and rods 3, a follower fitting over said tacks and rods and 85 held in place by keys through said rods, and a cap-covering secured upon the rods 3, substantially as shown and described.

In witness whereof I have hereunto set my hand this 25th day of February, 1886.

MINNIE B. McCASTLINE.

In presence of—

C. W. SMITH,

F. L. STEVENS.
